UNITED STATES PATENT OFFICE.

FRANK C. MASON, OF STREATOR, ILLINOIS, ASSIGNOR TO METAL STAMPINGS CORPORATION, OF STREATOR, ILLINOIS, A CORPORATION OF ILLINOIS.

WOOD-CENTER SWEEPER WHEEL.

Application filed July 9, 1925. Serial No. 42,355.

My invention relates to improvements in wheels and more particularly to wheels such as used for carpet sweepers, and other devices wherein it is desirable to have a strong 5 light weight wheel which can be manufactured at a comparatively low cost.

The object of this invention is to provide a wheel of strong but light weight construction, which may be manufactured principally 10 of stamped sheet metal parts and which will have a suitable bearing provided.

In the drawings which illustrate a selected embodiment of my invention,

Fig. 1 is a plan of a portion of a carpet 15 sweeper having a wheel embodying my invention used therewith.

Fig. 2 is a section on the line 2—2 of Figure 1, and

Fig. 3 is a section on a diameter of my 20 improved wheel, showing the parts as they appear when assembled, but before being fastened together.

Referring now to the drawings, wherein I have illustrated my improved wheel applied to a carpet sweeper, 5 designates the body of a carpet sweeper having the usual bumper cushion 6 around its edges, and a wheel retaining and cushion supporting member 7 secured to the body, one of which 25 is located at each side in the case of a carpet sweeper. The wheels 8 are disposed between the body 5 and member 7 and are rotatably mounted on a shaft 9, which shaft may be of any suitable diameter and may be either 30 a stub shaft secured in the body of the device, or a transversely extending shaft having a wheel mounted on each end.

My improved wheel comprises two discs 40 10 and 11, preferably made of sheet metal, having flanges 12 and 13 respectively. The internal diameter of the flange 12 is preferably such that it will be a snug fit over the external diameter of the flange 13. The disks 10 and 11 are preferably provided with 45 annular inclined shoulders 25 and 26, and these shoulders are preferably formed by pressing axial portions of the disks outwardly so as to form inwardly facing recesses 14 and 15 in the disks 10 and 11 respectively. The annular shoulders 25 and 50 26 are adapted to receive the opposite ends of a suitable bearing member 16 interposed between the disks, the end portions of the

bearing member being disposed within the annular shoulders and entering said inwardly facing recesses. The bearing member may be of oil soaked wood such as used in the so-called self-oiling bearings, or of any other analogous material and is preferably chamfered at its edges as at 17 and 18 55 so that the respective end portions fit snugly into the recesses 14 and 15. The chamfered edges of the bearing member and the inclined shoulders 25 and 26 cooperate to center the bearing member between the disks, 60 and to hold the bearing member against accidental displacement. An aperture 19 in the disc 11 admits a shaft to the bearing member while the disc 10 is preferably pressed out as at 20 to form a contact point 65 between the wheel and the retaining member 7. The flange 13 is of a width substantially the same as the desired tread width of the finished wheel, but the flange 12 is somewhat wider as shown at 21 in Figure 3. 70

When the wheel is to be assembled, a pair of discs having the above described construction are placed together as shown in Figure 3, a bearing member being interposed between the recesses 14 and 15. The overhanging lip 21 on the outer flange 12 is then swaged inwardly over the edge of the inner flange as at 22, Fig. 2, the inner flange 13 maintaining the spacing of the discs at their periphery. The edges of the disc at the 75 aperture 19 are pressed inwardly as at 23, Fig. 2, to more securely hold the bearing member. A suitable cushion tire 24 may be applied to the wheel, if desired.

In use, a wheel of the above described construction is placed on a shaft as shown in Figure 2 and a retaining member as 80 7 is positioned adjacent the outside of the wheel so that in case the wheel tends to run off the shaft, the contact point 20 of the wheel will 85 abut the retaining member and prevent the wheel from becoming disengaged, while at the same time producing no noticeable retarding friction.

My improved wheel has the desirable qualities of lightness, strength and cheapness in cost of manufacture and the above described 90 details of construction being merely illustrative of one phase of my invention, it will be understood that the scope of the same 100 should be determined by reference to the 105

appended claims, such claims being construed as broadly as possible, consistent with the state of the art.

I claim as my invention:

5. 1. A wheel comprising a pair of disks joined together at their peripheries to form the rim of the wheel and each having an axially disposed circular recess, a bearing member having circular end portions, the 10 outer edges of which are chamfered and disposed in the recess of the respective disks, said chamfered edges being effective to cause said bearing to be substantially self-centering between the disks.
15. 2. In combination with a wheel comprising a pair of disks joined together at their peripheries to form the rim of the wheel, and each having an axially disposed recess for receiving and positioning a bearing member 20 therebetween, a bearing member having a bearing aperture extending therethrough and having its opposite ends seated in said axial recesses, one of said disks having an aperture for admitting a shaft into said 25 bearing aperture and the other of said disks having a portion serving as a closure for said aperture, a shaft in said bearing aperture, and means cooperating with said closure portion for retaining the wheel on said 30 shaft.
35. 3. A wheel comprising a pair of discs each having an inturned peripheral flange, one of said flanges encasing the other and swaged over the outer edge thereof to retain it thus encased, said discs having centrally disposed circular recesses therein, and a bearing member having its ends interlocked with said recesses, one of said discs having an axial aperture to admit a shaft to said 40 bearing, and the other disc having an axial contact point pressed outwardly therefrom, said discs being spaced apart at their peripheries by means of the encased flange and at their axes by means of the said bearing member.
45. 4. A wheel comprising a pair of discs each having an inturned peripheral flange, one of said flanges encasing the other and swaged inwardly over the outer edge there- 50 of to retain it so encased, said discs having centrally disposed circular recesses therein and a bearing member disposed between said recesses, one of said discs having an axially disposed aperture to admit a shaft to the 55 bearing member and the other disc forming a closure at the other end of said bearing member.
60. 5. A wheel comprising a pair of discs each having an inturned peripheral flange, one of which encases the other and is swaged inwardly over the outer edge thereof to retain it so encased, said discs having centrally disposed circular recesses therein, and a bearing member disposed between said 65 recesses, one of said discs having an axially

disposed aperture to admit a shaft to the bearing member, the periphery of said aperture being pressed inwardly to grip said bearing member, and the other disc having an axially disposed contact point pressed outwardly therefrom, forming a closure at the other end of said bearing member. 70

6. In a wheel the combination of a pair of discs having inturned peripheral flanges, one of said flanges encasing the other and 75 swaged thereover at its outer edge, said discs also having centrally disposed circular recesses therein, a self-oiling bearing disposed in said recesses and clamped therebetween and having a bearing aperture extending therethrough, one of said discs being axially apertured to admit a shaft to said bearing aperture, and the other of said discs having a portion serving as a closure for the adjacent end of said bearing aperture and whereby said wheel is adapted to be positioned on the end of a shaft. 80

7. A wheel comprising a pair of discs having inturned peripheral flanges, one encasing the other and swaged thereover at its outer edge, said discs having centrally disposed circular recesses in said discs and a self-oiling bearing member having chamfered edges disposed in said recesses, said 90 chamfered edges being adapted to fit into said recesses to position said bearing member, one of said discs being axially apertured to admit a shaft to said bearing member, the edges of said aperture being pressed inwardly to grip said bearing member, the other disc having an axial contact point pressed outwardly and forming a closure at the other side of said bearing member. 95

8. In combination with a wheel comprising a pair of discs each having an inturned peripheral flange, one of which encases and embraces the other, said discs having centrally disposed circular recesses therein, and a bearing member disposed between said recesses, one of said discs being apertured to 100 admit a shaft to said bearing and the other of said discs having an axially disposed contact point pressed outwardly therefrom; a shaft in said bearing and a retaining member cooperating with said contact point to retain said wheel on said shaft. 110

9. A wheel comprising a pair of disks joined together at their peripheries to form the rim of the wheel, each of said disks being provided with an annular inclined shoulder concentric with the wheel, and a bearing member interposed between said disks and having its opposite end portions respectively disposed within said annular shoulders, the latter being effective to cooperate with the adjacent ends of the bearing member to center the same between the disks. 120

10. A wheel comprising a pair of disks joined together at their peripheries to form the rim of the wheel, each of said disks hav- 130

- ing an axial portion pressed outwardly so as to form an annular inclined shoulder, and a bearing member interposed between said disks and having its opposite ends respectively disposed within the annular inclined shoulder of the adjacent disk, said shoulders being effective to cooperate with the adjacent end portions of the bearing member to center the same between the disks.
- 5 11. A wheel comprising a pair of disks joined at their peripheries to form the rim of the wheel, each of said disks having an axial portion pressed outwardly so as to form an annular inclined shoulder, and a bearing member interposed between said disks and having circular end portions pro-
- vided with chamfered outer edges, said inclined shoulders and said chamfered edges being effective to cooperate to center the bearing member between the disks.
- 10 12. A wheel comprising a pair of disks joined together at their peripheries to form the rim of the wheel, each of said disks being provided with an annular inclined shoulder concentric with the wheel, and a bearing member interposed between said disks and having chamfered end portions respectively engaging said annular inclined shoulders, whereby the bearing member is centered between the disks.

FRANK C. MASON.
